UNITED STATES PATENT OFFICE.

JOHN E. PHILLIPS, OF CENTRAL SQUARE, NEW YORK.

DESIGN FOR A CREAM-SEPARATOR.

SPECIFICATION forming part of Design No. 30,244, dated February 21, 1899.

Application filed January 28, 1899. Serial No. 703,739. Term of patent 7 years.

To all whom it may concern:

Be it known that I, JOHN E. PHILLIPS, of Central Square, in the county of Oswego and State of New York, have invented and produced a new and original Design for Cream-Separators, of which the following is a specification, reference being had to the accompanying drawings, forming part thereof.

Figure 1 is a front view of a cream-separator, showing my design. Fig. 2 is a vertical transverse sectional view taken on line *w w* of Fig. 1.

As shown in the drawings, the leading or material features of my design consist of the vertical cylinder *A*, the flaring base *B*, situated directly beneath the aforementioned cylinder and its inclined periphery slanting outwardly from the cylinder's periphery, the diaphragm *a*, disposed directly at the bottom termination of the cylinder aforesaid at its junc-

tion with the flaring base and horizontally parallel therewith, said level diaphragm having the depression *b* in its front portion and an orifice *c* in such depression, and an opening *d* in the front of the hereinbefore-mentioned flaring base *B* on a plane beneath the diaphragm. 25

Having described my invention, what I claim as new, and desire to secure by Letters Patent, is—

The design for a cream-separator, as herein shown and described. 30

In testimony whereof I have hereunto set my hand in the presence of two attesting witnesses.

JOHN E. PHILLIPS.

Witnesses:

L. B. CAMPBELL,
I. M. CAMPBELL.
